UNITED STATES PATENT OFFICE.

FRED F. BURDICK, OF CHICAGO, ILLINOIS.

COLLAPSIBLE CABINET.

1,048,807.

specification of Letters Patent. Patented Dec. 31, 1912.

Application filed August 5, 1912. Serial No. 713,455.

To all whom it may concern:

Be it known that I, FRED F. BURDICK, a citizen of the United States, and a resident of Chicago, in the county of Cook and State 5 of Illinois, have invented certain new and useful Improvements in Collapsible Cabinets, of which the following, when taken in connection with the drawings accompanying and forming a part hereof, is a full and complete description sufficient to enable those skilled in the art to which it pertains to understand, make, and use the same.

This invention relates to cabinets which are adapted to be used by physicians, nurses 15 and other individuals, either continuously or occasionally, and which, when not in use are adapted to be collapsed into a less space than is occupied by the same when in operative condition.

20 The principal objects of this invention are to obtain a device which will meet all the requirements of physicians, nurses, specialists, and other persons, in and about the giving of what are commonly known as light baths, 25 Turkish or steam baths, Russian or hot air baths, medicated baths, including volatilization, with or without heat and with or without inhalation of volatilized or vaporized medicaments; and to obtain a 30 device which is simple in construction, efficient in service, economically made, not liable to get out of order, durable, and easily changed from an operative to an inoperative, (or collapsed) condition, by persons not particularly skilled in mechanics.

35 Additional objects are set forth in this specification and disclosed in the claims.

In the drawings Figure 1 is a perspective 40 of a collapsible cabinet embodying the invention, said cabinet being set up in an operative condition. Fig. 2 is a top plan view, with the top removed, and the parts shown in the position thereof which is illustrated in Fig. 1. Fig. 3 is a sectional view, on line 45 3-3 of Fig. 2, viewed in the direction indicated by the arrows, showing the top in place and a person seated in the cabinet. Fig. 4 is a front elevation of the upper part 50 of a person, showing a hood in vertical section, and a diaphragm in elevation, said parts forming elements in the device, and said diaphragm attached to said person. Fig. 5 is a vertical section on line 5-5 of Fig. 2, viewed in the direction indicated by

the arrows. Fig. 6 is a vertical section, exclusive of the top, hood and diaphragm, showing the several remaining parts in a collapsed or storage position. Fig. 7 is a top plan view of the several parts which are illustrated in Fig. 6, and in the same position 55 as in said Fig. 6. Fig. 8 is a top plan view of the top of the cabinet, with the several parts in the position required when the cabinet is in an operative, or set up position; but with the hood removed and a sliding 60 cover which forms an element of the device in place on said top. Fig. 9 is a section of the top of the cabinet, on line 9-9 of Fig. 8, viewed in the direction indicated by the arrows. Fig. 10 is an elevation of one of the 65 side panels of the cabinet. Fig. 11 is a section, on line 11 of Fig. 3, viewed in the direction indicated by the arrows. Fig. 12 is an elevation on line 12-12 of Fig. 5, viewed 70 in the direction indicated by the arrows, 75 and Fig. 13 is a top plan view of one corner of the device, showing the top of the tube which forms an element of the device.

A reference character applied to a given part is used to designate said part throughout the several figures of the drawings.

A, A', and B, B', are, respectively, the front and side panels of the cabinet. To avoid warping, shrinking, and the like I make these panels of sheet metal. Panels A, 80 A', are respectively made in two parts, a and a'. The parts a, a' of panel A are joined together by hinges a''. (See Figs. 5 and 7.) The vertical edges of panels A, B and B', and of A', B and B', which come adjacent to 85 each other at the corners of the cabinet, are joined together and to the posts or tubes C, by means of the straps (G, G'), which are hereinafter more particularly described. The construction which joins the panels and 90 the tubes C together includes the caps C' which are placed on the upper ends of the tubes C to close said ends.

D are rings, respectively provided with the inner annular flanges d. Said rings are 100 rigidly secured in the tubes C, at the lower ends thereof by rivets, or screws d'.

E are disks which are respectively provided with an annular groove, e, fitting over, to turn on, flange d.

F are posts, which are respectively screw threaded at their upper ends, and are provided with caster balls f at their lower ends.

Said disks E are rigidly secured together and on the posts F by threads which engage with the threads on posts F. The upper one of said disks forms a lock nut to 5 the lower one thereof.

G are straps which are respectively secured to panels A, and A', and G' are like straps which are secured on panels B, B'. g are rivets which secure said straps to said 10 panels.

H are lampholder bases, which are rigidly secured on tubes C by rivets or bolts h.

An upper and a lower strap G is secured to the respective panels A, A', and said 15 strap extends around the post C which is adjacent to a given edge of said panels, and in like manner an upper and lower strap G' is secured to the panels B, B'. On one of the straps G and on one of the straps G', at 20 a given corner, rectangular apertures g' are made, in which aperture a base H is movable, and through which aperture said base extends. When the panels of the cabinet are in the position illustrated in Fig. 1, 25 that is, in an operative position, one end of the aperture g' in a strap G is close to contact with the standard of the base extending therethrough, and the other end of the aperture in a strap G' is close to said base; and 30 when the panels are collapsed the opposite ends of said apertures are close to contact with the said bases. By this construction the lamp bases are held equally distant from the panels when the device is in operation, 35 and are prevented from coming in contact with said panels when said panels are collapsed, and the lamps (I) are prevented from being broken, without removal of said lamps from said bases.

40 I are the lamps of the device. As hereinbefore set forth said lamps are automatically put into proper position by means of slots g', when the panels are in an operative, or in an inoperative, (collapsed) 45 position.

J, Figs. 2, 3, 5 and 12, are connections which are respectively secured at their ends in the posts F, to lie parallel with the planes of panels B, B'. Connections J form the 50 supports on which the legs K of the seat base L are mounted. Said legs are respectively provided with a sliding sleeve, k, which sleeves are movable, to slide, on connections J. Seat base L consists of parts 55 l, l', (which are pivotally joined together by bolt L'), and the part l'', which is provided with the vertical screw threaded shaft l''. Part l'' is provided with an internally screw threaded aperture, the threads whereof fit the screw threads on shaft l'''. The legs K are respectively pivotally attached to the parts l, l', of seat base L.

M is a seat which is joined to seat base L by pivot or hinge m. When the cabinet is 60 collapsed the several legs K, the parts of

the seat base L, and seat M, are respectively forced into substantially the position in which they are illustrated in Fig. 6.

l''' are lugs on parts l, l', respectively, to engage with legs K when said seat is in the position which is illustrated in Fig. 5, to maintain said base and seat in a substantially horizontal position.

N is the top of the cabinet and is made of the parts n, n' and n''. Top N is simply laid on the upper edges or ends of the panels A, A', B, B', when the device is to be put into an operative position, and said top is removed from said panels when they are to be put into a collapsed or storage position. Parts n' are joined to the parts n by hinges O, and parts n'' are joined to parts n' by hinges O'.

P is a hood which is placed on top N when the use thereof is desired. It will be 85 observed that the several parts n, n' and n'' are of such shape and are so attached together that an aperture in the top formed by said parts is obtained, and that said aperture is considerably larger than is required to permit a person to put the head and body therethrough; and also, that when the hood P is used the parts n'' are turned up against the sides of said hood and there secured by the catch p, (see Fig. 1).

P' is a glass in hood P, and p' is a glass in panel A. Said glasses afford inspection by a person outside of the cabinet of a person within it.

Q, (Figs. 3 and 4), is a diaphragm made 100 of textile or other suitable material. The hood is removably attached to the top N by means of rods q fitting into brackets q'. Brackets q' are attached to the underside of top N.

R are electric conductors to supply an electric current to burners or lamps I.

S is a steam generator.

T is a vaporizer or volatilizer arranged to discharge into the cabinet.

t is a pipe or conduit of flexible material, arranged to be attached to the discharge end of the volatilizer T and to deliver its contents into or above the diaphragm Q.

T' is a pipe or conduit communicating 115 with the generator S and the vaporizer or volatilizer T, to conduct steam from said generator to said vaporizer.

U is a fresh air conduit and u is a valve in said fresh air conduit.

V, (Fig. 5), are shields which are made of opaque material, as sheet metal. Shields V are only used when it is desired to shut off the direct rays of light from the lamps which are in the cabinet, while at the same time making use of the heat emanating therefrom. When not in use they are folded up against the panels B, B', and to permit such folding they are attached to said panels by means of hinges W.

X is a movable cover which is provided with aperture X', and which is also provided with the slots X''. Slot X' fits reasonably close to the neck of a person in the 5 cabinet, and slots X'', being open at one end, permit the said cover to be slid along on the top N with studs X''' in said slots. Cover X consists of two parts which meet at y, (Fig. 8), and either or both said parts 10 are removable by simply sliding them along on the top N until the studs X''' are out of slots X''.

The contour line of the aperture in top N is indicated by broken line Y (Fig. 8), and 15 it will be observed that considerable movement of the cover X is obtainable on said top without uncovering said aperture, and I am thus enabled to slide the seat M toward the front or rear of the cabinet and to correspondingly move the cover X so that a person seated on said seat will be in a comfortable position.

The caps C' are secured to one of the panels, at each corner of the cabinet.

25 C'' are caps which are secured to the top N at each of the corners thereof, (see Figs. 1 and 8).

I claim:

1. The combination of two-part panels, 30 single panels and tubes, said panels joined to said tubes by straps arranged to turn on said tubes, and one of the parts of said two-part panels, respectively, joined to the other part by hinges, a removable top arranged to rest on the upper edges of said panels, bases 35 attached to the lower ends of said tubes, connections attaching the base of the tube at one edge of the single panels to the base of the tube at the other edge thereof, sleeves on 40 said connections, a seat base, and legs pivotally attached to said seat base and said sleeves.

2. The combination of two-part panels, single panels, and tubes, said panels joined 45 to said tubes by straps arranged to turn on said tubes, and one of the parts of said two-part panels, respectively, joined to the other part by hinges, a removable top arranged to rest on the upper edges of said panels, bases 50 attached to the lower ends of said tubes, connections attaching the base of the tube which is at one edge of the single panels to the base of the tube at the other edge thereof, sleeves on 55 said connections, a seat base, legs pivotally attached to said seat base and said sleeves, said top comprising parts joined together by hinges, and a hood removably mounted on said top.

3. The combination of two-part panels, 60 single panels, and tubes, said panels joined to said tubes by straps arranged to turn on said tubes, and one of the parts of said two-part panels joined to the other part by hinges, a removable top arranged to rest on 65 the upper edges of the said panels, said top

consisting of parts joined together by hinges, and said parts arranged to provide an aperture in said top, with an additional part arranged to be placed over said aperture.

4. The combination of two-part panels, 70 single panels, and tubes, said panels joined to said tubes by straps arranged to turn on said tubes, and one of the parts of said two-part panels joined to the other part by hinges, a removable top arranged to rest on 75 the upper edges of said panels, said top consisting of parts joined together by hinges and said parts arranged to provide an aperture in said top, and a hood removably mounted on said top over said aperture. 80

5. The combination of two-part panels, single panels, and tubes, said panels joined to said tubes by straps arranged to turn on said tubes, apertures in one of the straps at the edges of the respective panels, and lamp 85 bases extending through said apertures and attached to said tubes, said apertures positioned to prevent a lamp in said bases from contact with said panels, and to turn said tubes and place said lamp bases in a determined position when the said panels are in position to obtain an operative cabinet, with a top mounted on said panels. 90

6. The combination of two-part panels, single panels, and tubes, said panels joined 95 to said tubes by straps arranged to turn on said tubes and one of the parts of said two-part panels joined to the other part by hinges, a removable top arranged to be mounted on the upper edges of said panels, 100 said top provided with an aperture, an additional part arranged to be placed over said aperture, with a diaphragm, the upper edges of said diaphragm attachable to said top and the lower edges thereof attachable to a person in the cabinet obtainable by said panels and top. 105

7. In a cabinet, the combination of tubes, panels, and straps, both ends of a given strap secured to a corresponding panel and extended around said tubes, to turn thereon. 110

8. In a cabinet, the combination of tubes, panels, and straps, said straps secured to said panels and extended around said tubes; to turn thereon, and caps on the upper ends 115 of said tubes, and said caps secured to one of the panels adjacent to said tubes.

9. In a cabinet, the combination of tubes, panels, and straps, said straps secured to said panels and extended around said tubes, 120 an aperture in one of the straps which is attached to one of the panels and an aperture in one of the straps which is attached to the other panel at each corner of said cabinet, and lamp bases extending through said respective apertures, with lamps on said bases. 125

10. In a cabinet, the combination of tubes, panels, and straps, said straps secured to said panels and extended around said tubes 130

to turn thereon, a top provided with an aperture therein, said top arranged to rest on the upper ends of said panels, and a diaphragm removably attached to said top and 5 attachable to a person in said cabinet.

11. A cabinet consisting of side walls and a top thereon, said top provided with an aperture, in combination with a two part cover to said aperture, said two part cover 10 provided with an aperture and with slots which are open at their respective ends on one side of said parts, and studs to said top, said cover movable on the top with said studs in said slots and removable from said top.
15. 12. The combination of two-part panels, single panels, and tubes, said panels joined to said tubes by hinges and one of the parts of said two part panels joined to the other

part by hinges, a removable top arranged to rest on the upper part of said panels, 20 said top provided with an aperture therethrough, an additional part arranged to cover said aperture and removable therefrom, lamp bases in said tubes and lamps in said bases, with opaque shields removably 25 placeable in the cabinet obtainable from said panels and top, said shields arranged to obstruct rays of light from said lamps and to transmit the heat therefrom into said cabinet.

Signed at Chicago, Cook county, Illinois, this 30th day of July, 1912.

FRED F. BURDICK.
In presence of—
H. P. PALMER,
EUGENE WHEELER.
